FIG. 1

To all whom it may concern:

Be it known that I, Joseph R. Mango, a citizen of the United States and resident of Midlothian, in the county of Cook and State of Illinois, have invented a new, original, and ornamental Design for a Beverage Server, of which the following is a specification, reference being had to the accompanying drawing, forming a part thereof.

Fig. 2 is a rear elevational view thereof;

Fig. 3 is a front elevational view thereof; and

Fig. 4 is a top plan view thereof.

I claim:

The ornamental design for a beverage server, substantially as shown.
